CLAIM

The ornamental design for a fluid trap for a respiratory device, as shown and described.

DESCRIPTION

FIG. 1 is a front, top, and left side perspective view of a fluid trap for a respiratory device embodying our new design.

FIG. 2 is a front, bottom, and side perspective view thereof; FIG. 3 is a top view thereof;

FIG. 4 is a bottom view thereof;

FIG. 5 is a first side view thereof;

FIG. 6 is a second side view thereof;

FIG. 7 is a front view thereof; and,

FIG. 8 is a rear view thereof.

Broken lines are used to illustrate portions of the fluid trap for a respiratory device that form no part of the claimed design.

1 Claim, 7 Drawing Sheets
